SHIRT BUNDLING RACK

Ephraim Cohen, 2424 Sylvale Road, Baltimore,
Md. 21209

Filed Mar. 21, 1967, Ser. No. 6,320

Term of patent 14 years

(Cl. D49—1)

FIG. 1

FIG. 2

FIG. 3

FIG. 5

The broken line representation of a support base in FIGURE 1 is for purposes of illustration only.

I claim:

The ornamental design for a shirt bundling rack, as shown and described.
